UNITED STATES PATENT OFFICE.

GEORGE H. HESS, OF LA GRANGE PARK, ILLINOIS.

FURNACE.

1,358,370.

Specification of Letters Patent.

Patented Nov. 9, 1920.

Application filed June 28, 1920. Serial No. 392,818.

To all whom it may concern:

Be it known that I, GEORGE H. HESS, a citizen of the United States, residing at La Grange Park, in the county of Cook and State of Illinois, have invented a new and useful Improvement in Furnaces, of which the following is a specification.

My invention relates, more particularly, to improvement in hot-air furnaces; and my primary object is to provide in a furnace having means whereby the products of combustion, under the control of the operator may be caused to pass through a substantially direct course from the combustion chamber into the flue, or through a tortuous course to the flue, for the utilization to the maximum degree of the heat generated by the furnace for heating air discharged from the furnace into the rooms to be heated, and the minimizing of danger of the escape of the products of combustion into the heating-air. A further object is to provide a structure which shall be of simple construction and comparatively economical to manufacture, and other objects as will appear from the following.

Referring to the accompanying drawings:

Figure 1 is a perspective view of a furnace constructed in accordance with my invention. Fig. 2 is a rear view of the same. Fig. 3 is a view in side elevation of the structure shown in Fig. 1 with certain parts broken away, and parts shown in section. Fig. 4 is a section taken on the line 4—4 Fig. 3 and viewed in the direction of the arrow, this section being taken through the rear side of the furnace at a point directly above the smoke pipe. Fig. 5 is a face view of a damper controlling the passage of the products of combustion directly to the smoke pipe from the combustion chamber. Fig. 6 is a section taken at the line 6—6 on Fig. 7 and viewed in the direction of the arrows; and Fig. 7 a vertical section taken through the structure shown in Fig. 6 and showing the jacket.

My invention is equally applicable to furnaces of the so-called "pipe" type, as well as to furnaces of other types as for example that of the pipeless type, and I therefore do not wish to be understood as intending to limit it to the type of structure shown. The furnace illustrated is formed of a chamber 8 which may be of the general rectangular shape in cross section as shown,

this chamber constituting a combustion chamber and containing in its lower portion a fire-box 9 which extends short of the rear wall of the chamber 8 as shown, the fire-box 60 being of any desirable construction. The chamber 8 is shown as supported on cross-pieces 10 at the front and rear of the furnace, the rear cross-piece only being shown. Surrounding the chamber 8 and preferably 65 spaced therefrom throughout its extent, is a jacket 11 providing therebetween a hot-air space 12 through which air admitted thereto, by any suitable opening as is common in practice, passes upwardly for becoming 70 heated by the products of combustion, and thence from the space 12 through any suitable opening, or openings, (not shown) for leading the hot air to the point of use thereof. The front wall of the combustion chamber 8 contains an opening 14 communicating with one end of a framing member 15 open at its opposite ends and located within the air space 12, the outer end of this framing 75 communicating with an opening (not 80 shown) in the front wall of the jacket 11, and forming the firing opening controlled by a door 16 hinged at 17 to the front wall of the jacket 11. As shown, the furnace also is formed with an ash-door 18 controlling a passage leading into the fire-box below the grate, and with a door 19 controlling a passage opening into the fire-box at about the level of the upper surface of the grate therein as is common in furnace structures. 85 90

In constructing a furnace in accordance with the preferred embodiment of my invention, the metal forming the rear wall of the combustion chamber 8 is deflected, as 95 by pressing it, outwardly in a lateral direction to form a channel represented at 17 which extends substantially vertically and preferably from the lower end of the chamber 8 to within a short distance of its top, 100 the proportions of this deflected portion being such, preferably, as to cause the outermost wall portion 18 thereof, to be spaced from the adjacent, rear, wall of the jacket 11. A plate member, represented at 19, is 105 positioned to close the inner side of the channel 17 from its upper end to a point closely adjacent to its lower end, this plate being secured in any desirable way, as by riveting it at intervals, as represented at 20 110 or securing it in any other suitable way, against the inner surfaces of the rear wall

of the jacket 11 at opposite sides of the channel 17, it being preferred that the joint between the plate 19 and the wall of the combustion chamber 8 be practically 5 gas-tight. The structure just described forms a flue which is located within the hot-air space 12 and through which the hot products of combustion are caused to pass, in the normal operation of the furnace on 10 their way to the outlet of the furnace which communicates with the usual smoke-pipe, thereby augmenting the heating of the air in its passage through the air space 12, the products of combustion in the operation of 15 the furnace as stated, entering the flue through the opening, represented at 21 and which, in the particular construction illustrated, is formed by the plate 19 reaching short of the bottom portion of the chamber 8.

The plate 19 toward its upper end, and in the position shown in the drawings slightly above the upper edge of the firebox 9, contains an opening 22 arranged substantially in line with openings 23 and 24, in the wall 18 of the flue and the rear wall of the jacket 11, respectively, there being provided in the opening 24 and connected with the wall 18, to register with the opening 23 and to form a gas-tight connection with the said wall, a pipe 24^a through which the products of combustion are conveyed away from the furnace. The opening 22, in coöperation with the other parts just described, forms a direct passage for the products of combustion from the combustion chamber to the outlet of the furnace. Damper means are illustrated for controlling the opening and closing of this direct 40 passage, these means, as shown, comprising a tubular member 25 shown as cylindrical and containing offset lugs 26 and 27 on its inner surface, this member being riveted as indicated at 28, or otherwise suitably secured, to the outer surface of the plate 19. Coöoperating with the opening provided through the member 25 is a damper 28 shown in the form of a disk with portions thereof deflected in opposite directions into 45 angular position as represented at 29 and 30 and through which deflected portions a pivot pin 31, square in cross section, extends, its upper and lower circular extremities being journaled in the member 25. A plate 32 extends through a slot 33 in the damper 28 and contains a square hole (not shown) through which the pivot pin 31 extends and with which it is interlocked to permit the 55 damper 28 to be turned by swinging the plate 33, which contains at its outer end an elongated slot 34 into which a depending arm 35 rigid on a bar 36 rotatably mounted in the plate 19, wall 18 and rear wall of the jacket 11, extends. The outer end of the

shaft 36 has a crank arm 37 pivotally connected with a link 38 connected with a crank arm 39 on a shaft 40 journaled in brackets 41 on the jacket 12, the opposite end of the shaft 40 having a crank arm 42 connected by a universal joint 43 with a link 44 pivoted in a lug 45 on the furnace door 16, the parts being so arranged that when the door 16 is swung open it will, through the mechanism described, move the damper 28 to open condition, and when this door is 75 swung to closed position will close the damper 28.

The flue formed by the closed channel 17, is preferably provided with a damper represented at 46 and shown in the form of a 80 plate mounted on a rock shaft 47 journaled in openings in the plate 19, wall 18 and rear wall of the jacket 11, the outer end of this rock shaft having a handle portion 48 by which the damper may be set in any desired 85 position in the flue.

It will be understood that in the normal operation of the furnace the passage, controlled by the damper 28, is closed to the combustion chamber and consequently the 90 products of combustion are forced to pass to the inlet 21 of the flue through which latter they pass upwardly to the outlet of the furnace, the hot products of combustion thus being required to pass through an indirect path on their way out of the furnace and in passing through the flue formed by the closed channel 17, serve to provide increased heat-radiating surfaces for contact by the air in the air space 12, thereby augmenting heating action on the air and thereby utilizing to a high degree, the heat units for heating the air to be delivered from the furnace. When the fire door 16 is opened the damper 28 is automatically opened and a direct passage for the products of combustion from the combustion chamber 8 to the 100 outlet of the furnace, is provided.

A very desirable feature of my construction consists in forming the flue located in the air space 12, by deflecting laterally in an outward direction, the metal of the wall of the combustion chamber, inasmuch as not only may the furnace be economically constructed, but danger of escape of the gases from the combustion chamber into the air passage, is eliminated as this part of the structure is free of joints between the passages through which the products of combustion pass and the air space, it being observed that the joints between the plate 19 and the walls of the channel 17, are located between passages both of which are traversed by products of combustion, viz., the combustion chamber and the flue.

While I have illustrated and described a particular construction embodying my invention, I do not wish to be understood as

intending to limit it thereto, as the same may be variously modified and altered without departing from the spirit of my invention.

What I claim as new and desire to secure 5 by Letters Patent is:

1. In a hot-air furnace, the combination of a combustion chamber, a jacket between which and the wall of said chamber a hot-air space is provided, the wall of said chamber being deflected laterally to form a channel, a plate secured to the wall of said chamber to form, with said deflected portion, a flue in said hot-air space, said flue containing openings at different elevations communicating with said chamber and the furnace being provided with an outlet communicating with said flue, the upper opening in said flue forming a passage from said chamber to said outlet for the relatively 10 direct travel of the products of combustion from said chamber to said outlet, and the lower opening in said flue forming a passage for the relatively indirect passage of said products to said outlet, and means 15 whereby the products of combustion, under the control of the operator, may be permitted to pass through either the upper or lower opening in said flue.
2. In a hot-air furnace, the combination 20 of a combustion chamber, a jacket between which and the wall of said chamber a hot-air space is provided, the wall of said chamber being deflected laterally to form a channel, a plate secured to the wall of said chamber to form, with said deflected portion, a flue in said hot-air space, said flue containing 25 openings at different elevations communicating with said chamber and the furnace being provided with an outlet communicating with said flue, the upper opening in said flue forming a passage from said 30 chamber to said outlet for the relatively direct travel of the products of combustion from said chamber to said outlet, and the lower opening in said flue forming a passage for the relatively indirect passage of 35 said products to said outlet, the furnace containing an outlet in communication with said third opening, the upper one of said first-referred-to openings forming, with said third opening in the 40 flue, a passage from said chamber to said outlet for the relatively direct travel of the products of combustion from said combustion chamber to said outlet and the lower one of said first-referred-to openings form-

ing with said third opening, a passage for 50 the relatively indirect passage of said products to said outlet, and means whereby the products of combustion may be permitted to pass, under the control of the operator through either the upper or lower one of the 55 first-referred-to openings.

3. In a hot-air furnace, the combination of a combustion chamber, a jacket between which and the wall of said chamber a hot-air space is provided, the wall of said chamber being deflected laterally to form a channel, a plate secured to the wall of said chamber to form, with said deflected portion, a flue in said hot-air space, said flue being in 60 communication at its lower end with said 65 chamber, the outlet of said flue being above its inlet.

4. In a hot-air furnace, the combination of a combustion chamber, a jacket between which and the wall of said chamber a hot-air space is provided, the wall of said chamber being deflected laterally to form a channel, a plate secured to the wall of said chamber to form, with said deflected portion, a flue in said hot-air space, said flue containing 70 openings at different elevations communicating with said chamber and the furnace being provided with an outlet communicating with said flue, the upper opening in said flue forming a passage from said 75 chamber to said outlet for the relatively direct travel of the products of combustion from said chamber to said outlet, and the lower opening in said flue forming a passage for the relatively indirect passage of 80 said products to said outlet, a pipe section secured to said plate and communicating with the uppermost one of said first-referred-to openings and so constructed and arranged as to permit of either the direct or 85 indirect passage referred to, and means, including a damper device in said pipe section, whereby the products of combustion may be permitted to pass, under the control of the operator, through either the upper or lower 90 one of the first-referred-to openings.

GEORGE H. HESS.
